UNITED STATES PATENT OFFICE.

JAMES W. ARTHUR, OF AKRON, OHIO, ASSIGNOR TO THE WILLIAMS FOUNDRY & MACHINE COMPANY, OF AKRON, OHIO, A CORPORATION OF OHIO.

PLURAL-PART MOLD.

1,315,200.

Specification of Letters Patent. Patented Sept. 9, 1919.

Application filed May 12, 1919. Serial No. 296,457.

To all whom it may concern:

Be it known that I, JAMES W. ARTHUR, a citizen of the United States, resident of Akron, Ohio, have invented certain new and 5 useful Improvements in Plural-Part Molds, of which the following is a specification.

My present invention relates to improvements in vulcanizing apparatus designed for the repair of rubber foot wear and aims to 10 provide a simple, economical, durable and efficient equipment designed to enable foot wear of various shapes to be neatly and expeditiously repaired.

The invention includes the novel features 15 of construction and arrangement and combination of parts hereinafter described and defined by the appended claims, an embodiment of the invention being illustrated in the accompanying drawings, in which:—

20 Figure 1 is a front elevation of the apparatus.

Fig. 2 is an elevation at right angles to Fig. 1.

25 Fig. 3 is an enlarged sectional detail of the dome or head.

Figs. 4, 5 and 6 are details of the exterior parts of the means for holding the boot or shoe while vulcanizing the sole.

30 Figs. 7, 8 and 9 are detail views of the horn and plates carried thereby.

Referring by reference characters to this drawing the numeral 1 designates a standard for supporting the various parts of the equipment which may be held in vertical 35 position by any suitable base such as the feet or legs 1^a as shown.

This standard is hollow and is designed to act as a fuel reservoir for containing liquid fuel, which may be supplied to the burner 2 40 by compressed air which may be forced into the upper part of the reservoir above the fuel level either by a hand pump or any other convenient source (not shown). A filling pipe and funnel 8 is provided for 45 introducing fuel into the standard.

Above the burner is located a boiler 3 of any suitable type designed to supply steam for heating the vulcanizing members, this boiler being conveniently secured to the 50 standard by a two part clip 4 embracing the standard and boiler. The boiler is preferably provided with a water gage glass 5, a filling pipe and funnel 6, and a pressure gage 7.

55 Secured to the top of the standard is a

head dome or member 9 which carries the vulcanizing members hereinafter described and which also serves as a steam collecting and return space, the steam from the horns returning into this space, and, with any water of condensation being returned to the boiler by pipe 10, provided with a cut-off valve 10^a. The head is provided on one side with a plurality of openings 9^a, two being shown in the drawings as a convenient member, into which are designed to be inserted the inner ends of vulcanizing horns 11. The horns are provided with flanges 11^a fitting corresponding rabbets in the side of the head, and the horns are detachably held in position by clamping plates 12 secured to the head by tap screws or bolts 13, the clamping plates having integral sleeves or flanges 12^a which embrace the sides of the horns and increase the strength and rigidity of the 75 connection.

The openings 9^a and corresponding parts of the horns are made round so that the horns may be turned on their horizontal axes to bring the foot portions at any angle. 80

Projecting from the opposite side of the head is a soling plate or table 14 having a suitably curved upper surface beneath which is a steam chamber 15 to which steam from the boiler is supplied by a pipe 16. I prefer 85 to lead the steam to the horns from this steam space as in this manner I can supply steam to the horns without interfering with the ready removal thereof, and to this end I provide a pipe 17 leading from the steam 90 space directly across the head 9 and axially into each horn, each pipe being provided with a cut off valve 18 having a stem projecting through the top of the head where it carries a suitable operating handle, this providing means for cutting off the steam supply in changing horns. 95

It is desirable that the steam pipes 17 should extend clear into the toe portions of the horns as shown in dotted lines, Fig. 1 100 and to provide for using shorter horns for different characters of foot wear each pipe is made with a removable pipe portion 17^a, detachably connected with the main portion by a detachable coupling 17^b of any approved type. 105

To secure the requisite pressure upon the portion of the foot wear being repaired or vulcanized, I provide the following instrumentalities.

Supported from a suitable collar 18 on the standard are a pair of parallel bracket arms 19 preferably round in cross section which lie directly beneath the horns and 5 have upwardly curved outer portions 19^a. The arms 19 have transverse openings 19^b through which is passed and slidably held a horizontal bar 20. Associated with each 10 arm is a band pulling device indicated at 21 for applying pressure to the part being repaired, each having a threaded shank adapted to pass through an eye or opening in a member 20^a having a laterally projecting curved arm adapted to underlie either 15 one of the arms 19, 19^a, as shown on the right of Fig. 2 or the bar 20 as shown on the left of Fig. 2, according to the position of the last and foot wear. These band pulling arms comprise each a curved portion 21^a 20 having at the extreme end lugs supporting a bolt or pin 21^b which serves as a means for attachment of the end of a pressure band 22.

The arms are provided with a widened 25 out portion above the threaded shank which has a central opening or passage through which the band is passed and attached to or wound about a shaft or spindle 23 journaled in suitable bearing lugs or portions 21^c 30 of the arms 21. This shaft is provided with a crank handle 23^a by means of which, after the band has been adjusted over the part to be vulcanized, it can be wound on the shaft to secure the requisite pressure. Pawl 35 and ratchet means indicated at 24 is provided to hold the shaft against reverse movement.

The threaded portion of each arm 21 is provided with a wing nut 25 enabling vertical adjustment of the arm with relation to 40 number. When the band carrying arm is to be applied the curved part of bracket or member 20^a is located beneath the arm 19 or the rod 20 with the band overlying the 45 boot or shoe in which position it will be self-supporting, and thereafter the band tightened to the desired degree as above described.

The table 14 is designed for acting on 50 the sole of the boot or shoe and to this end has its upper surface suitably curved or concaved as shown, and in conjunction with this I use sole vulcanizing plates 26 adapted to rest on said curved surface and 55 be heated thereby. These sole plates 26 have an upper surface designed to conform to the surface of the sole to be repaired or replaced, and are provided with a plurality of marginal pins or projections 26^a designed 60 to be detachably and interchangeably engaged by the lower ends of the tension members or straps 27 which are connected at their upper ends to a bracket member 28 slidably carried on the horizontal portion 65 29^a of the horn or leg last 29 and locked

in any desired position thereon by lock screw 28^a.

This horn or leg last is shaped at its lower end to project forwardly into the toe portion of the boot or shoe as indicated at 70 29^b where it is provided with removable and changeable yielding means for bearing against the insole. Such means preferably comprises a plurality of superimposed flexible plates 30, 30^a and 30^b of graduated size, the desired resiliency of the edges being secured by notching the edges as indicated at a. The plates are secured to the under 75 face of the portion 29^b by means of bolts, the plates being preferably provided with elongated slots b having enlarged portions b' designed to permit the passage of the bolt heads and enabling the plates to be locked on the last or horn by a longitudinal movement which brings the heads of the 80 bolts over the narrower portions of the 85 openings.

By using a plurality of superimposed resiliant plates I get a maximum of resistance 90 for large articles of foot wear when all the plates are used which may be successively reduced for smaller articles by the successive removal of the outer plates.

It is sometimes found desirable to support the vulcanizing outfit hereinbefore described from a wall or connect it thereto, and to this end I provide the head or dome with a laterally extending arm 31 provided with a plate 31^a designed to be bolted to a 95 wall or other stationary vertical member. 100

Having thus described my invention what I claim is:

1. In combination a suitable supporting member, a work supporting horn projecting laterally therefrom, means enabling said horn to be adjusted about its horizontal axis, and means for applying exterior pressure to a desired portion of the article carried by the horn. 105
2. In combination a suitable support, a work supporting horn carried thereby, a bracket arm located below the horn, a band carrying arm adjustably carried by the bracket arm and having a curved part overhanging the horn, a pressure band having one end attached to the end of said curved part, and means acting on the other end of the band for tensioning the same. 110
3. In combination a suitable support, a work supporting horn carried thereby, a bracket arm located below the horn, a band carrying arm adjustably carried by the bracket arm and having a curved part overhanging the horn, a pressure band having one end attached to the end of said curved part, a spindle journaled in said band carrying arm and provided with a hand crank and to which spindle the other end of said band is connected, and means for locking said spindle against reverse movement. 115
4. In combination a suitable support, a work supporting horn carried thereby, a bracket arm located below the horn, a band carrying arm adjustably carried by the bracket arm and having a curved part overhanging the horn, a pressure band having one end attached to the end of said curved part, a spindle journaled in said band carrying arm and provided with a hand crank and to which spindle the other end of said band is connected, and means for locking said spindle against reverse movement. 120
5. In combination a suitable support, a work supporting horn carried thereby, a bracket arm located below the horn, a band carrying arm adjustably carried by the bracket arm and having a curved part overhanging the horn, a pressure band having one end attached to the end of said curved part, a spindle journaled in said band carrying arm and provided with a hand crank and to which spindle the other end of said band is connected, and means for locking said spindle against reverse movement. 125
6. In combination a suitable support, a work supporting horn carried thereby, a bracket arm located below the horn, a band carrying arm adjustably carried by the bracket arm and having a curved part overhanging the horn, a pressure band having one end attached to the end of said curved part, a spindle journaled in said band carrying arm and provided with a hand crank and to which spindle the other end of said band is connected, and means for locking said spindle against reverse movement. 130

4. In combination a suitable support, a plurality of horizontally disposed horns supported therefrom, a bracket arm extended beneath each horn, a cross bar adjustably supported by said several brackets, band carrying means supported by said cross bar and overhanging the horns, and means for tensioning the bands. 50
5. In combination a suitable support, a plurality of horizontally disposed horns supported therefrom, a plurality of bracket arms beneath the horns, a cross bar adjustably supported by said brackets, band carrying means supported by said cross bar and overhanging the horns, one of said band carrying means being displaced laterally from the vertical plane of the horn to a greater distance than the other of said band carrying means, and means for tensioning 55 the bands.
6. In combination a steam head or dome, a horizontally disposed horn removably connected to the side thereof, and having its interior communicating with the dome, a steam supply pipe extending through the dome and into the foot portion of the horn, and a steam exit from said dome. 60
7. In combination a steam head or dome, a horizontally disposed horn removably connected to the side thereof and having its interior communicating with the dome, an extensible steam supply pipe extending through the dome and into the foot portion of the horn, and a steam exit from said dome. 65
8. In combination a steam head, a steam table supported at one side thereof, a hollow horn supported at the other side thereof, and in communication with said head, a steam pipe leading from the steam space of said table through the head into the extremity of the horn, a boiler, a pipe leading from the boiler to the steam table, and a steam return pipe from the head to the 70 boiler.
9. In combination a hollow head, a steam table at one side thereof, a plurality of hollow horns removably and interchangeably carried by the other side, a plurality of steam pipes extending from said steam space through the head and into said horns, said pipes having removable portions, valves for said pipes, means for supplying steam to said table, and a steam outlet from said head. 75
10. A presser plate for use in vulcanizing foot wear comprising a plurality of superimposed sheets of resilient material of different areas. 80
11. A presser plate for use in vulcanizing foot wear comprising a plurality of superimposed sheets of resilient material of different areas having slotted or notched edges. 85
12. A presser plate for use in vulcanizing foot wear comprising a plurality of superimposed sheets of resilient material of different areas, detachably connected together. 90
13. In combination a last or tree member and a presser member composed of a plurality of superimposed sheets of resilient material of different areas. 95
14. In combination a mold plate, a tree having a lateral arm, and straps connected with said lateral arm at one end and means for connecting the opposite ends of said straps with the edges of the mold plate at different points. 75
15. In combination a mold plate having a series of projections on each side edge, a tree, and straps connected with the upper end of said tree and having recesses in their lower ends adapted to receive said projections. 80
16. In combination a tree having an angularly turned upper end, a block adjustably carried by said end, a mold plate, straps connected to said block and means for removably and adjustably connecting the lower ends of said straps to the edges of said mold plate. 85

In testimony whereof, I affix my signature.

JAMES W. ARTHUR.
